MICROTOME AND ATTACHMENT THEREFOR

Donald M. Crooks, Tucson, Ariz.

Application April 23, 1936, Serial No. 75,990

7 Claims. (Cl. 88—40)

This invention relates to improvements in microtomes and attachments therefor.

An object of the invention is to provide means by which a microtome may be made to cut a series 5 of sections from two planes of the same specimen in alternate succession.

Another object is to provide a device of the above character which may be readily attached to a standard microtome.

10 Another object is to provide a device of the above character in which the shift from one plane to the other may be readily accomplished by hand.

Another purpose is to provide means by which 15 the device may be retained accurately in each cutting position.

A further object is to provide means by which the shift from each cutting position to the other may be accomplished automatically by the operation of the microtome.

20 Other objects and advantages of the invention will become apparent during the course of the following description, in connection with the accompanying drawing, in which—

Figure 1 is a bottom view of the specimen 25 mounting device;

Figure 2 is an end view of the same;

Figure 3 is a view partly in section showing the device in position for cutting in one plane;

Figure 4 is a view similar to Figure 3, but showing 30 the platen mounting shifted for cutting in the second plane;

Figure 5 shows a typical specimen embedded in a suitable matrix or holding block;

Figure 6 shows a succession of sections cut from 35 the specimen, Figure 5, in one plane;

Figure 7 illustrates a series of sections cut from the same specimen alternately in two planes by means of the present invention;

Figure 8 shows the device clamped in the head 40 of a typical microtome; and

Figure 9 illustrates means by which the shifts from one cutting position to the other may be made automatically by the operation of the microtome.

45 Referring to Figures 1, 2, 3 and 4, the numeral 10 indicates a yoke member having a shank 11 adapted to be secured between upper and lower clamping members 12 and 13 of the head 14 of a microtome 15 such as that shown in Fig. 8. A 50 platen holder 16 is mounted on tapered pivots 17 and 18 adjustably threaded into the arms of the yoke 10.

Formed on the holder 16 is a segment 19 having at the extremities of its arcuate surface radially 55 extending stops 20 and 21 adapted to engage the

yoke 10 when the holder is swung into the positions shown in Figs. 3 and 4 respectively, thus accurately defining the two cutting positions, the arc of swing in the device as shown comprising ninety degrees.

A latching plunger 22, Figs. 3 and 4, is slidable in a hole 23 in the shank 10. A spring 24, backed by a retaining plug 25, urges the plunger 22 forward to engage notches 26 and 27 in the segment 19, by which means the platen holder is retained in either cutting position. A cross pin 22^a spanning a flat 22^b on the plunger 22 retains the latter in the shank 11 in case the holder 16 is disassembled from the yoke 10.

A pin 28 extends laterally from the segment 19 and forms a convenient handle by which to move the holder 16 from either position to the other. The pin 28 obviously may be located on the other side of the segment or a pin may be provided on each side.

A platen 29, adjustably secured to ways 29^a on the holder 16, by means of screws 74 in slots 75, Fig. 2, has a scored surface 30 adapted to receive and hold a block 31 of paraffin or the like in which is embedded a specimen 32 from which it is desired to cut sections, a typical block and specimen being shown in perspective in Fig. 5.

Referring to Fig. 8, the microtome 15 comprises a base 33 to which is secured a pair of vertical slide rails 34. A carriage 35, vertically slidably on rails 34, has secured thereto horizontal guides 36 and 37 between which is disposed a horizontally slid- 30 able block 38. A drive shaft 39, rotatably mounted in an upright support 40 on the base 33, terminates in a crank 41 having a crank-pin 42 journaled in the block 38.

The head 14 is slidable horizontally in the carriage 35, and is adapted to be fed to the left by any suitable mechanism 48 which may include a feed screw shaft 43 provided with a ratchet wheel 44. As such feed mechanisms are well known in the art and as their specific details have no bearing on the present invention, no further description of their structure is necessary herein. The clamping members 12 and 13 of the head 14 are 45 provided with a clamping screw 45 in order to grip the shank 11 as previously described.

An upwardly directed knife 46 is clamped in a support 47 mounted on the base 33.

The operation of the device is as follows: The 50 supporting block or matrix 31 is mounted on the scored surface 30 of the platen 29, the paraffin being softened to cause it to adhere firmly thereto. The block 31 is so placed that the corner containing the specimen 32 projects beyond the 55

edge of platen 29 and the shank 11 is gripped in the jaws 12 and 13 so as to bring the block 31 adjacent the edge of the knife 46, the platen holder 29 first being swung to the downward position shown in Fig. 4. The shaft 39 is revolved by means of a crank or hand wheel (not shown), causing the crank 41 to reciprocate the carriage 35 vertically in the rails 34, the block 38 sliding horizontally between guides 36 and 37. By this means the specimen block 31 is carried upward and downward past the knife 46. The feed mechanism 48 advances the head 14 to the left until on a downward stroke of the carriage the knife 46 cuts a slice 49 from the bottom of the block 31, as shown in Fig. 4. When the carriage 35 has returned to the top of its stroke, the holder 16 is swung into its upper position, thus revolving the block 31 so as to present its end plane in line with the knife. A revolution of the microtome then causes a slice 50 to be cut from the end of the block, as shown in Fig. 3.

By repeated shifts of the holder 16 between cutting strokes, it is evident that a series of sections may be cut from the block 31 and specimen 32 alternately in two planes.

When a series of slices is cut from a paraffin block in the manner described, each completed slice adheres to the outer edge of the knife 46. The next successive slice moving downward from the cutting edge pushes the previous slice ahead of it, and during this action the edges of the slices cohere or stick together, so that a series of slices comes off the microtome in the form of a continuous ribbon. Figure 6 illustrates such a ribbon comprising sections 50^a, 50^b, 50^c, 50^d, from a specimen such as 32 when cut in one plane in the ordinary manner. The sections 50^a, 50^b, 50^c, etc., are all similar to slice 50, and obviously present the aspect of the specimen only in the single plane.

Figure 7 shows a ribbon comprising successive sections 49^a, 50^a, 49^b, 50^b, etc., the sections being cut in two planes by means of the present invention. Each cross section, such as 50^a, is immediately preceded by and joined to a corresponding longitudinal section 49^a. For example, if a plant stem be used as a specimen, the result is a ribbon comprising alternate longitudinal and cross sections of the stem arranged in continuous order.

By the use of the invention as described, it is obviously made possible to perform interpretations of specimen structures with greater accuracy and completeness than with previous cutting devices. For example, in the case of a microscopic tissue examination of a duct or a bundle of blood vessels, the technician is enabled to examine the duct or bundle in successive cross sections as it encounters the cutting edge and then to observe the same duct or bundle in longitudinal section between its nearest cross sections in the same ribbon. The advantage of the above ability to examine a single specimen in successive and directly related cross and longitudinal sections is of especial importance in histological analysis in large hospitals and the like, since tissue is often pathic only in localized areas and no accurate interpretation could be made from sections taken from separate blocks.

A further advantage of the device is the fact that from a knowledge of the number of sections taken and their thickness as determined by the feed of the microtome, the dimensions of a specimen or any part thereof may be accurately determined in two directions.

It is obvious that as a section is cut from each

plane at every second revolution, the feed of the microtome is set at one-half the desired thickness of slice.

When it is desired to render the shifting of the holder 16 automatic, the device shown in Fig. 9 is employed. A bracket 51, secured to the head 14, carries at its extremity a pin 52. A claw 53, pivotally mounted on the pin 52, is adapted to engage the outer side of pin 28 in the segment 19 when the holder 16 is swung upward as shown. A vertical link 54 connects an extension 55 of the claw 53 with a lever 56 pivoted to an upright 57 forming part of a bracket 58 secured to the microtome base 33. A second claw 59, also pivotally mounted on the pin 52, is adapted to engage the pin 28 in segment 19 when the holder 16 is swung into downward position. A second link 60 connects an extension 61 of claw 59 with a second lever 62 pivoted to a second upright 63 on the lower bracket 58.

A rod 64, pivotally attached to the pin 28, is slidable in a sleeve 65 pivoted on the pin 52 of bracket 51. A spring 66 urges the rod 64 outward, thus forming a toggle combination which tends to force the holder 16 into either upper or lower position whenever the pin 28 is to the left or right respectively of the line of centers between the pin 52 and the tapered pivots 17 and 18.

A cam shaft 67, journaled in a pedestal 68 on the bracket 58, is adapted to be driven at one-half the speed of the microtome shaft 39 by any suitable means such as a chain 69 and the sprockets 70 and 71. A cam 72 on the shaft 67 overlies the free end of the lever 56, while a second cam 73 arranged at 180 degrees with cam 72 and offset therefrom along the shaft 67, overlies the free end of lever 62.

The operation of the automatic shifting means is as follows: Assuming the holder 16 to be in upper cutting position, as shown in Fig. 9, during the cutting stroke and during the upward stroke of the head 14 the lever 56 swings freely below the cam 72 until the block 32 has cleared the knife 46. Thereafter, as the upward movement of the head 14 continues, the lever 56 encounters the lobe of cam 72 which restrains further upward motion of the lever and link 54. As the pivot pin 52 continues to move upward, the stopping of link 54 causes the claw 53 to be swung counter-clockwise, moving the pin 28 past dead center as shown in dot-and-dash lines, Fig. 9, and at the same time compressing the toggle spring 66. After the pin 28 has been forced over dead center, the spring 66 re-expands to continue the movement of the pin 28 until the holder 16 is swung completely into its lower cutting position.

The following downward stroke of the head 14 causes a section to be cut from the bottom of the block 31 as previously described. After the block 60 has cleared the knife 46 on the next upward stroke the lever 62 encounters the lobe of cam 73, the cam shaft 67 having revolved 180 degrees since the previous engagement of lever 56 with cam 72. The upward movement of lever 62 and link 60 is thereby restrained, causing the record claw 59 to move the pin 28 upward and to the left past its dead center, after which the toggle spring 66 operates in the manner described to return the holder 16 to its initial cutting position 70 as shown.

As the levers 56 and 62 are operable by separate cams set at 180 degrees, each lever is free to idle while the other is in operation, while both levers idle during the cutting strokes and during 75

the return strokes until the block 31 has been carried above the knife 46, so that no interference between the claws or improper shifting of the holder 16 can occur. The use of the toggle 5 as described to complete the shifting movements makes unnecessary any exact or delicate adjustment of the movements of the claws 53 and 59, and the length of links 54 and 60 is sufficiently great that the horizontal movement of the head 10 14 due to feed has no effective influence on the automatic shifting action.

From the foregoing, it is evident that the continued rotation of the microtome shaft 39 will cause the device to be shifted automatically to 15 produce a series of sections cut alternately from two planes of the specimen and forming a continuous ribbon as previously described.

While the invention has been described in preferred form, it is not limited to the exact structures illustrated, as various modifications may 20 be made without departing from the scope of the appended claims.

What is claimed is:

1. In a specimen holding device for use on a 25 microtome including a knife and a movable head cooperative therewith, in combination, a yoke, a shank on said yoke and adapted to be attached to said head, a holder pivotally mounted in said yoke, a platen adjustably secured to said holder 30 and adapted to retain a specimen, whereby said specimen may be presented to said knife by motion of said head, means to rotate said holder and specimen between two positions in said yoke, stops on said holder adapted to engage said yoke 35 whereby said positions may be pre-determined, and means in said shank and engaging said holder to automatically latch said holder in each of said positions.

2. In a specimen holder for a microtome, in 40 combination, a support, a holding member pivotally mounted thereon and rotatable thereon between two positions through an angle of substantially ninety degrees, said member being formed with an arcuate surface having terminal 45 notches therein, means to secure a specimen to said holder, and latching means in said support and adapted to automatically engage said notches to retain said holding means in either of said positions.

50 3. In a microtome having a base, in combination, a knife, means on said base to support said knife, a mounting head, means on said base to movably support said head adjacent said knife, means pivotally mounted on said head and 55 adapted to hold a specimen, feeding means to advance said head and specimen toward said knife, means to move said head across said knife whereby sections may be cut from said specimen by said knife, means to swing said holding means 60 back and forth through a pre-determined angle whereby said sections may be alternately cut from said specimen in two non-parallel planes,

and resiliently controlled means to latch said holding means in each of two positions determining the limits of said angle.

4. In a microtome, in combination, a base, a knife, means on said base to support said knife, a mounting head movably supported on said base adjacent said knife, means pivotally mounted on said head to hold a specimen, feeding means to advance said head and specimen toward said knife, means to move said head across 10 said knife whereby sections may be cut from said specimen by said knife, means to rotate said holding means between two predetermined cutting positions whereby two non-parallel planes of said specimen may be alternately presented 15 to said knife, and resilient means to control said rotating means including a spring-pressed latch engaging said holding means and adapted to retain the same in each of said two positions.

5. In a specimen holding device for use on a 20 microtome including a stationary knife and a movable head cooperative therewith, in combination, a yoke, a shank on said yoke and adapted to be attached to said head, a holder pivotally mounted in said head, means on said holder to 25 retain a specimen whereby said specimen may be presented to said knife, means to rotate said holder and specimen between two positions in said yoke, stops on said holder adapted to engage said yoke whereby said positions may be 30 pre-determined, and a spring-pressed latch in said yoke engaging said holder to retain the same in each of said two positions.

6. In a microtome adapted to cut successive sections from a specimen pivotally held thereon, 35 in combination, a stationary knife, feeding means to advance said specimen toward said knife, means to move said specimen across said knife to cut said sections, and means connected to said moving means and operable thereby to rotate said specimen back and forth through a 40 set angle of substantially ninety degrees whereby two substantially perpendicular planes of said specimen may be alternately presented to said knife.

45 7. In a microtome, in combination, a stationary knife, a movable mounting head adjacent said knife and cooperative therewith, means on said head to hold a specimen, said holding means being pivotally mounted on said head, feeding 50 means to advance said head, holding means and specimen toward said knife, means to move said head, holding means and specimen across said knife whereby sections may be cut from said specimen by said knife, manually operable means 55 to rotate said holding means between two predetermined cutting positions whereby two non-parallel planes of said specimen may be alternately presented to said knife, and resilient means to latch said holding means in each of 60 said cutting positions.
